PAINT PAIL

Garth A. Showers, Tannersville, N. Y., assignor of one-half to Minnie K. Cole, Tannersville, N. Y.

Application August 2, 1957, Serial No. 47,204

Term of patent 14 years

(Cl. D58—17)

Fig.1

Fig. 2

The side not shown is the same as the side shown.

What is claimed is:

The ornamental design for a paint pail, as shown and described.
